RADIO RECEIVING AND SOUND
REPRODUCING APPARATUS

John E. Brady, Somerset, Md.

Application December 5, 1952, Serial No. 324,293

10 Claims. (Cl. 250—16)

1

My invention relates broadly to radio receiving and sound reproducing apparatus and more particularly to a radio receiver and sound reproducer built into a desk calendar stand.

This application is a continuation-in-part of my application Serial No. 24,177, filed April 30, 1948, for Radio Receiving Apparatus, now abandoned.

One of the objects of my invention is to provide a construction of a compact radio broadcast receiver built into the hollow base of a desk calendar stand.

Another object of my invention is to provide a compact construction of radio broadcast receiver assembled within the hollow base of a desk calendar stand which encloses an electrical sound reproducer arranged to emanate sound vibrations through one wall of the desk calendar stand.

A further object of my invention is to provide a compact construction of radio broadcast receiver installed within the hollow base of a desk calendar stand of sheet metal construction, wherein the calendar stand forms a capacity area constituting the antenna or radio frequency pick-up means for the radio broadcast receiver.

Still another object of my invention is to provide a construction of substantially bifurcated chassis for the radio broadcast receiver housing miniature electron tube assemblies, shaped to fit within the inverted pan base of a desk calendar stand.

A still further object of my invention is to provide a construction of electrical sound reproducer built into a desk calendar stand and utilizing the properties of the base of the desk calendar stand as an aid in the reproduction of tones through the sound reproducer.

Other and further objects of my invention reside in the arrangement and assembly of a miniature electrical sound reproducer and a miniature radio broadcast receiver within the hollow base of a desk calendar stand as set forth more fully in the specification hereinafter following by reference to the accompanying drawing, in which:

Figure 1 is a longitudinal sectional view through a desk calendar stand showing the assembly therein of a radio broadcast receiver embodying miniature electron tube apparatus and circuit components and a miniature electrical sound reproducer, the view showing a fragmentary side elevation of the desk calendar stand for illustrating the tuning control extended exteriorly thereof; Fig. 2 is a plan view looking at the underside of the desk calendar stand and

5 showing the electrical sound reproducer and the radio broadcast receiver installed therein; Fig. 3 is a view of the rear of the desk calendar stand through which the sound emanates from the miniature electrical sound reproducer within the base; Fig. 4 is a transverse sectional view taken substantially on line 4—4 of Fig. 2; Fig. 5 is a schematic view illustrating the electrical connection of the radio broadcast receiver with the electrically conductive sheet material forming the calendar stand, where the calendar stand constitutes the capacity area comprising the antenna of the radio broadcast receiver; Fig. 6 is 10 a vertical cross-sectional view through a desk calendar stand utilized as an electrical sound reproducer in accordance with my invention; Fig. 7 is a horizontal sectional view taken substantially on line 7—7 of Fig. 6; Fig. 8 is a vertical 15 sectional view taken substantially on line 8—8 of Fig. 6; Fig. 9 is a fragmentary top plan view of the electrical sound reproducer installed in the desk calendar stand, certain of the parts being shown in horizontal section; Fig. 10 is a vertical 20 sectional view taken substantially on line 10—10 of Fig. 6; and Fig. 11 is a fragmentary schematic 25 view illustrating the manner of establishing electrical connection with the sound reproducer within the calendar stand through an impedance matching transformer installed within the calendar stand.

Referring to the drawings in detail, reference character 1 designates the metallic base of a desk calendar stand formed as an inverted pan, having a maximum height at the rear thereof designated at 1a, and a minimum height at the front thereof designated at 1b. The calendar stand has an inclined plane surface 1c thereon which serves as a support and mounting means for the multi-leaf calendar pad 1d which is secured in position by means of transverse binding plate 2 fastened by means of adjustable screws 3 having finger-gripping heads 4 thereon and which pass through the binding plate 2 and through the stack of calendar leaves 1d and through the screw-threaded strip 5 which extends transversely of the calendar stand beneath the inclined plane supporting plate 1c thereof. At the front of the calendar stand there is provided a compartment 6 in which there is disposed the rockable shelf 7 which serves as a carrier for the stack of separate memoranda sheets 8. The front edge of the rockable shelf 7 projects beyond the front of the calendar stand and is provided with a resilient friction drag edging 9, serving as a fric-

tion drag against the bottom sheet of the stack of memoranda sheets 8, thus facilitating individual withdrawal of memoranda sheets as the rockable shelf is moved out of engaging position with respect to the terminating front edge 1e of the calendar pad supporting plate 1c. The rockable shelf 7 has a rear edge portion 7a thereon which is connected to a biasing spring 10 to a lug 1f extending downwardly from the calendar pad supporting plate 1c.

The calendar pad stand thus described is the invention of Harold G. Davis, as set forth in Letters Patent 2,422,474 of June 17, 1947, Calendar Stand With Memoranda Paper Supply, and Letters Patent 2,425,925 of August 19, 1947, Calendar Stand With Memoranda Paper Supply Device.

The calendar stand 1 is formed from electrically conductive material and is utilized in the radio receiving apparatus of my invention as a radio frequency energy pick-up means or antenna.

The calendar stand is substantially insulated from ground by means of supporting feet of insulating material represented at 11, 12, 13 and 14. The supporting feet 13 and 14 are mounted on a transversely extending strip 15 adjacent the rear of the calendar stand. The calendar stand is thus insulatingly supported with respect to the ground on any suitably supporting surface 16.

The rear end of the calendar stand 1 is apertured as represented at 17 to receive the grill work 18. Internally of the calendar stand and substantially aligned with the grill work 18 I provide an electrical sound reproducer which I have designated generally at 19. The electrical sound reproducer is of miniature size and fits within the calendar base at the maximum dimensioned end 1a thereof. The calendar base tapers from the maximum dimensioned end 1a to the minimum dimensioned end 1b and serves in effect as a horn tending to direct sound waves forwardly and toward the rear end of the calendar stand where all vibrations emanate through the open grill work 18. The sound reproducing diaphragm of the electrical sound reproducer 19 directs sound vibrations outwardly through the grill work 18 of the calendar base. The electrical sound reproducer is connected by a flexible cable, designated at 20, to the output of a radio receiver mounted in chassis 21. The chassis serves as a baffle displaced to the rear of the electrical sound reproducer in the tapered chamber formed by the pan constituting the calendar stand, directing the sound vibrations from the rear of the electrical sound reproducer outwardly through the grill work 18 of the calendar base in reinforcement of the sound vibrations emanating from the front of the electrical sound reproducer. In the form of my invention illustrated herein, the tapered chamber extends behind the sound reproducer for a distance which is a multiple of the depth of the sound reproducer 19. The depth of the tapered chamber behind the rear of the electrical sound reproducer is approximately four times the depth of the sound reproducer 19. The radio receiver mounted in chassis 21 includes an electron tube apparatus of miniature size in which all of the electrical components, including vacuum tubes, transformers, condensers, resistors, and impedance devices, are of miniature construction to fit compactly within the container formed by chassis 21. The chassis 21 is slotted throughout a central portion at 22 to clear the spring actuating device 10 which controls the operation of the rockable shelf 7. The chassis 21 thus provides a pair of housing por-

tions 23 and 24 containing the components of the radio broadcast receiver which I have designated as housed within the dotted line 25, in Fig. 4. The chassis 21 is electrically insulated from the metallic wall of the calendar stand 1 by means of separators of insulation material, which I have designated at 26 and 29 between the side walls 1g and 1h of the calendar stand and the chassis 21. The fastening screws 45 which pass through the side walls of the calendar stand for securing the radio receiver chassis 21 in position enter the insulator separators 26, 27, 23 and 29 and not the chassis 21 of the radio broadcast receiver, for insuring the electrical isolation of the chassis 21 from the sheet metal of the calendar stand.

To prevent grounding of the chassis to the underside of the calendar pad supporting plate 1c, I provide limiting stops of insulation material 30 and 31 fastened to the under surface of the inclined plane calendar pad supporting surface 1c. These limiting stops of insulation material 30, 31 have the form of a pair of longitudinally extending strips of insulation material which insure a positive space between the chassis 21 and the electrically conductive calendar pad supporting surface 1c.

In Fig. 5 I have illustrated the electrical connection of the inverted pan metallic base 1 to the radio broadcast receiver within the chassis 21. The coupling circuit for the radio broadcast receiver has been illustrated as including primary inductance 32 coupled with secondary inductance 33 connected with tuning circuit 34 which connects to the miniature electron tube system and circuit components constituting the miniature radio broadcast receiver. Primary coupling coil 32 is selectively connected by conductor 35 with the metallic sheet material of the calendar stand 1, whereby the calendar stand 1 serves as a capacity area or radio frequency energy collecting means insulated from the ground through supports 11, 12, 13 and 14. A separate ground connection 36 extends through an insulating grommet 37 in the side wall 1g of the calendar stand and connects to an adjustable clip 38 which may be clipped to any suitable ground.

The power supply for the radio broadcast receiver is furnished through flexible power line connecting cord 39 having power plug 40 connected thereto adapted to be inserted in the standard 110-volt, 60-cycle A.-C. power supply receptacle. The flexible cord 39 extends through insulation grommet 41 in the side wall 1h of the calendar stand and connects to the power supply rectifier and power supply circuits of the radio broadcast receiver in chassis 21. The tuning control for the radio broadcast receiver represented at 34 is operated externally of the side wall of the calendar stand, as represented at 42 for adjusting the circuits of the radio broadcast receiver to respond to desired broadcast frequencies and for operating the radio broadcast receiver over the broadcast frequency range with reference to the calibrated scale 43 on the side of the calendar stand.

The antenna connection 35 of the radio broadcast receiver chassis 21 extends out from the chassis 21 in insulated relation thereto at 46 and is detachably connected to the transverse strip 15 by means of detachable eyelet lug 47 fastened by screw 48. This arrangement facilitates the installation and removal of chassis 21 from the open bottom of the calendar stand for servicing maintenance and replacement of

burned-out tubes or other circuit components. Adequate lengths of leads are provided in conductors 36 and 39 to permit removal of the chassis 21 from the open base for maintenance operations thereon, while the conductors 36 and 39 remain threaded through insulated grommets 49 and 50 in the side wall 1h of the calendar stand aligned with insulated grommets 37 and 41 in chassis 21. The cover of the chassis 21 is readily removable and replaceable to provide access to the radio receiving apparatus within the chassis.

An "On" and "Off" switch 44 extends through the side wall of the calendar stand from chassis 21 for conveniently turning the radio broadcast receiver on and off.

The radio broadcast receiver to all outward appearances is a desk calendar stand containing the conventional annually renewable desk calendar pad. The device is, therefore, attractive as an office appliance and is readily merchandisable as a self-contained package unit. In certain instances it may be desirable to include a dry cell power supply within the base of the calendar stand in lieu of the 110-volt, 60-cycle A.-C. power supply connection hereinbefore described.

In Figs. 6-11 I have shown in more detail the manner in which the electrical sound reproducer is mounted within the base of the desk calendar stand 1 to secure all of the advantages of the tapered hollow base and directing the sound vibrations through the grill work 18 at the rear end of the calendar stand. I have shown the electrical sound reproducer 19 mounted as an assembly and readily insertable as a production unit through the under side of the open hollow base of the desk calendar stand 1. The unit is assembled on a transversely extending strip 51 which is secured to the opposite interior sides of the hollow base 1 as represented at 52 and 53 and provides a support for the angle members 54 between which the electrical sound reproducer unit 55 is assembled. The electrical sound reproducer unit consists of the cylindrical permanent magnet 56 having a hollow center in which the permanent magnet core 57 is mounted by means of screw 58 which passes through the permanent horseshoe magnet 59. A plate 60 extends across the permanent magnet 56 and across the holes of permanent magnet 59 and is centrally apertured for the passage of the bobbin supporting sleeve 61 extending from the sound reproducing elliptically frusto-conical diaphragm 62. The diaphragm 62 is supported at its periphery between rims 63 and 64 suitably secured to the rim of the diaphragm. The rims 63 and 64 are supported by vertically extending brackets 65 and 66 which are fastened to the transversely extending strip 51. The front of the conical-shaped diaphragm 62 has the rim 63 thereof aligned with the grill work 18 while the rear of the diaphragm 62 is substantially free of any obstruction so that sound waves propagated rearwardly from the diaphragm 62 follow a path represented generally at 67 through the follow base of the desk calendar stand impinging upon the baffle-like structure 6a formed by the rear of compartment 6 and the rear-edge portion 7a of the rockable shelf 7 from which the sound waves are reflected in paths designated generally at 68 for reinforcing the sound waves 69 emanating from the front of the diaphragm and directed through the grill work 18.

The proportions respecting the effective depth 75

of the sound reproducer compared with the depth of the chamber behind the sound reproducer heretofore pointed out to be in the ratio of 4 to 1 has been indicated in Fig. 7 where the effective depth of the sound reproducer 19 is indicated as x while the depth of the chamber behind the sound reproducer is indicated as $4x$. These proportions have been found to sustain the tones emitted at the grill work 18 at maximum efficiency.

The cylindrical portion 61 of the sound reproducing diaphragm carries the winding 69 which operates within the intense permanent magnetic field established through permanent magnet 56 and core 57 for converting the electrical impulses supplied through primary winding 70, impedance matching transformer 71 and secondary winding 72 into sound vibrations. The electrical connections from winding 69 are supported by the surface of the diaphragm 62 from which flexible leads extend to the terminals of secondary winding 72. The connections to primary winding 70 extend to a terminal strip indicated generally at 73 secured to the under surface of the desk calendar stand. From the terminals on terminal strip 73, a connection extends through flexible lead 74 passing through grommet 75 to a position exteriorly of the desk calendar base terminating in a plug 16. The plug may be engaged in a jack box mounted beneath the desk or table and to which leads extend from an intercommunication circuit or broadcast circuit for operation of the sound reproducer within the desk calendar base.

35 The hollow base of the desk calendar stand is closed by a plate 77 which is secured to the bottom of the compartment 6 and to the transverse strip 51 and carries the feet 11, 12, 13 and 14 which insulate the structure from the supporting 40 surface represented at 16. The plate 77 closes the hollow base providing the horn-like hollow chamber from which the sound waves are projected through the rear of the desk calendar stand.

I have found the structures of my invention, as 45 set forth herein, practical and efficient in operation, and while I have described my invention in certain of its preferred embodiments, I realize that modifications may be made, and I desire that it be understood that no limitations upon 50 my invention are intended other than may be imposed by the scope of the appended claims.

What I claim as new and desire to secure by Letters Patent of the United States is as follows:

55 1. Radio receiving apparatus including an antenna formed by a capacity area, a miniature radio receiving apparatus and a miniature sound reproducer connected therewith, said capacity area being shaped to provide a tapered relatively shallow substantially horizontally extending casing increasing in section from one end to the other end thereof and enclosing said radio receiving apparatus and sound reproducer on substantially three sides thereof and forming a support therefor, said sound reproducer being mounted within the end of said casing which is of largest section with the front of said sound reproducer aligned with the wall of the largest section end of said casing and the rear of said sound reproducer directed toward the smallest section end of said casing, said capacity area having an inclined plane calendar pad top supporting surface thereon, and means for insulatingly supporting said capacity area with respect to ground.

2. Radio receiving apparatus comprising an

antenna formed by a metallic sheet shaped as an inverted substantially horizontally extending relatively shallow pan and tapering from a minimum section at one end to a maximum section at the other end and insulatingly mounted with respect to earth and forming a support, the external surface of said pan extending in an inclined plane and forming a calendar pad support, a miniature chassis carrying radio receiving apparatus thereon and mounted within but spaced from the interior of said metallic sheet forming the inverted pan, and a sound reproducer electrically connected with said radio receiving apparatus with the front of said sound reproducer aligned with the wall of the maximum section end of said pan and the rear of said sound reproducer directed toward the minimum section end of said pan and mounted within the end of the inverted pan which is of maximum section and operative through the end of the inverted pan of maximum section for projecting sound vibrations.

3. In a radio receiving apparatus, a casing formed from electrically conductive material shaped as a relatively shallow substantially horizontally disposed inverted pan and tapered from a maximum altitude at one end to a minimum altitude at the other end, and forming a plane support for a calendar pad on the top thereof, a miniature electrical sound reproducer mounted within said inverted pan in the end thereof of maximum altitude with the front of said sound reproducer aligned with the wall of the maximum altitude end of said pan and with the rear of said sound reproducer directed toward the minimum altitude end of said inverted pan, a miniature radio receiving apparatus mounted within said inverted pan and electrically connected with said sound reproducer, said inverted pan being electrically connected with said radio receiving apparatus and constituting a collector of radio frequency energy, and means for electrically insulating said inverted pan with respect to earth.

4. A radio receiving apparatus comprising a calendar pad stand formed from electrically conductive material constituting an antenna and having an inclined calendar pad top supporting surface extending from a maximum height at one end of the stand to a minimum height at the other end of the stand and disposed in a substantially horizontally extending plane, a miniature electrical sound reproducer mounted within the maximum height end of said stand with the front of said reproducer aligned with the wall of the maximum height end of said stand and with the rear of said sound reproducer directed toward the minimum height end of said stand and operative for projecting sound vibrations through the end of the stand with the rear of said sound reproducer directed toward the minimum height end of said stand, a miniature radio receiving apparatus mounted within said stand and electrically connected with said electrical sound reproducer, an electrical connection from said radio receiving apparatus to said stand whereby said stand operates as an antenna, and means for insulatingly supporting said stand with respect to the earth.

5. Radio receiving apparatus comprising a calendar pad stand formed from electrically conductive sheet-like material shaped in the form of a relatively shallow substantially horizontally extending pan tapering from a maximum height at its rear end to a minimum height at its front end for supporting a calendar pad in inclined

position, said pan being apertured at its rear end, a sound reproducer mounted within said pan and operative for projecting sound vibrations through the apertured rear end of said pan, with the front of said sound reproducer aligned with the apertured rear end of said pan and the rear of said sound reproducer directed toward the minimum height end of said pan, and a miniature radio receiving apparatus having its input connected with said pan as an antenna and its output connected with said electrical sound reproducer.

6. A radio receiving apparatus comprising a calendar pad stand formed from electrically conductive sheet-like material including front and rear portions, side wall portions, and an inclined calendar pad top supporting portion extending from a maximum height at the rear of said stand to a minimum height at the front of said stand in a generally horizontal direction, a miniature radio receiving apparatus supported in electrically insulated relation to the interior of said stand, said radio receiving apparatus having an input circuit and an output circuit with the input circuit thereof electrically connected with said calendar stand as an antenna, a miniature electrical sound reproducer mounted within said stand at the maximum height end thereof and operative to project sound vibrations through the rear of said stand, with the front of said sound reproducer aligned with the rear wall of said stand and the rear of said sound reproducer directed toward the minimum height end of said stand, an electrical connection between the output of said radio receiving apparatus and said electrical sound reproducer, and means for electrically insulating said calendar stand with respect to earth.

7. In an apparatus of the class described, a tapered relatively shallow hollow base structure extending longitudinally in a generally horizontal direction from an end section of minimum cross-sectional area to an end section of maximum cross-sectional area, an electrical sound reproducer mounted in the end section of maximum cross-sectional area in said hollow base structure with the front of said sound reproducer aligned with the maximum cross-section end of said hollow base structure, said electrical sound reproducer directing sound vibrations outwardly through the last-mentioned end section of said base structure with the rear of said electrical sound reproducer directed toward the end section of minimum cross-sectional area, said base structure forming a tapered chamber behind the rear end of said electrical sound reproducer, and a radio receiver chassis disposed within said tapered chamber spaced from the rear of said electrical sound reproducer and forming a baffle for reflecting sound vibrations forwardly through the end section of maximum cross-sectional area in said base structure.

8. In an apparatus of the class described, a relatively shallow hollow base structure terminating in a sheet delivery device at one end thereof with a centrally extending spring member disposed between the sheet delivery device and a position within said hollow base structure, and a radio receiver chassis mounted within said hollow base structure, said chassis having a central slot therein fitting around said centrally extending spring member and projecting on both sides of the central slot in said chassis.

9. In an apparatus of the class described, a relatively shallow hollow base structure termi-

nating in a sheet delivery device at one end thereof with a centrally extending spring member disposed between the sheet delivery device and a position within said hollow base structure, and a radio receiver chassis mounted within said hollow base structure, said radio receiver chassis having a central portion and a bifurcated portion with the bifurcated portion fitting around said centrally extending spring member.

10. In an apparatus of the class described, a relatively shallow hollow electrically conductive base structure terminating in a sheet delivery device at one end thereof with a centrally extending spring member disposed between the sheet delivery device and a position within said hollow base structure, and a chassis for electrical ap-

paratus insulatingly supported within said hollow electrically conductive base structure, said chassis having a central portion and a bifurcated portion with the bifurcated portion fitting around said centrally extending spring member.
